UNITED STATES PATENT OFFICE.

CHARLES L. BARTLETT, OF UTICA, NEW YORK.

DESIGN FOR A HOLDER FOR TOOTH-POWDER.

SPECIFICATION forming part of Design No. 18,018, dated January 17, 1888.

Application filed December 13, 1887. Serial No. 257,825. Term of patent 3½ years.

To all whom it may concern:

Be it known that I, CHARLES L. BARTLETT, of Utica, in the county of Oneida, and in the State of New York, have invented a new and useful 5 Design for a Receptacle or Holder for Tooth-Powder; and I do hereby declare that the following is a full, clear, and exact description thereof, reference being had to the accompanying drawing, making a part of this specification, in which the figure shows a perspective view of my newly-designed receptacle for tooth powder or preparation.

The main part of the body A of the receptacle, as shown, is nearly but not quite cylindrical—that is, it is made slightly tapering upward. From the lower edge of the part A the receptacle is rounded outward and then downward. This outward swell B joins at its lower edge the upper edge of a second outward and downward swell, B', whose lower edge forms the bottom of the receptacle-sides. From the upper edge of the main part or body A the sides of the receptacle are curved outward, upward, and then inward again, forming a swell or bead, C. From this swell the top of the receptacle tapers upward, as shown,

with a concave taper. Around such top, just above the swell or bead C, are three annular rounded beads, C' C² C³. The upper end of the tapering top is shown flat. Over such end 30 fits the conoidal or thimble-shaped cap D. In the flat upper end of the receptacle-top are shown holes c c c for exit of the receptacle contents. The bottom E is shown as flat and provided with a central opening. 35

Having thus described my invention, what I claim is—

The design for a receptacle or holder, consisting of the two successive swells around its lower edge and the swell or bead around its 40 upper edge, the tapering top, and the conoidal or thimble-shaped cap on the upper end of the receptacle-top, substantially as described and shown.

In testimony that I claim the foregoing I 45 have hereunto set my hand this 26th day of November, 1887.

CHARLES L. BARTLETT.
